5 Claims. (Cl. 30—1)

The purpose of this invention is to provide an improved construction of sheep shear for avoiding a defect in previous commercial types of such shears, which defect consists in the tendency of the wool, when it is quite heavy or coarse, to resist the shearing action of the cooperating comb and cutter teeth, and to crowd the cutter off from the comb, thus making a more or less extended contact along the opposed faces of the comb and cutter, but preventing proper shearing engagement of these parts with each other,—with the result that the stubble left by the shearing is very undesirably variant in length.

The invention consists in the elements and features of the construction shown and described as indicated in the claims.

In the drawings:

Figure 1 is a fore-and-aft sectional view of a sheep shear embodying this invention.

Figure 2 is a top plan view of the same with the cover plate removed.

Figure 3 is a plan view of a pressure-applying plate which constitutes a feature of the invention, the same being illustrated in operative relation 25 to the cutter-blade-vibrating fork, which is shown in dotted lines.

Figure 4 is an edge elevation of the parts shown in Figure 1.

Figure 5 is a view similar to Figure 3, showing 30 correspondingly modified forms of the pressure plate and blade.

Figure 6 is a view similar to Figure 4, of the form shown in Figure 5.

Figure 7 is a view similar to Figure 3, showing 35 a second modification.

Figure 8 is a view similar to Figures 4 and 6, of the modification shown in Figure 7.

Figure 9 is a detail forward elevation showing 40 a modified form of means of engagement of the vibrating cutter blade by the pressure-applying plate.

Figure 10 is a detail side elevation of the parts shown in Figure 9.

Referring to the drawings in detail:

45 In Figures 1 and 2 there may be seen a customary form of sheep shear having a handle indicated at A, for carrying at its forward end the shearing cutters including the fixed-cutter-comb, M, and the vibrating cutter blade, N, the said handle carrying pivoted thereon the operating lever, F, which at its forward end engages the vibrating cutter blade, N, and at its rear end has the vertical cam slot, f¹, for engagement by a roller, p², on the crank wrist, p¹, of the operating head, P¹, 50 of the driving shaft, P. For engaging the vi-

brating blade, N, the lever, F, is furnished at its under side with a terminal plate, F³, having pin teeth, f³, for engaging the pin holes in the vibrating cutter blade, N, as seen in Figures 1 and 2.

The handle element, A, carries also a pressure-applying plate, B, for holding the vibrating cutter blade pressed firmly onto the fixed cutter and comb while it is vibrated by the lever; and a tension pin, L, extending between an adjustable stop, A⁵, mounted in an upwardly extending arch 10 or limb, A⁴, of the handle, A, and pivot seat provided in the pressure-applying plate, B, as seen at G.

In the form shown in Figures 1 to 4, the pressure-applying plate, seen at B, is spaced slightly 15 up from the forked cutter-blade-vibrating lever, F, at front and rear ends,—at the front end by the downwardly curved forward end terminals, D, which rest upon the correspondingly formed terminals of the forked lever, the latter having 20 slight upwardly projecting bosses, shown at E, for stopping any forward thrust of the pressure plate on the lever, and thereby on the cutter blade, and at the rear end by a screw, C, set in the pressure plate and protruding through it into 25 encounter with the lever, F, at a point indicated at f¹. The pressure is applied to the pressure plate by the familiar tension pin L, set in the customary tension cup, G, which, it may be understood, is carried by the customary arch A⁴, rigid 30 with the base which carries also the comb M with whose combining-and-cutting teeth the teeth of the cutter blade co-operate for shearing.

In the form shown in Figures 5 and 6 the pressure plate B¹ has the down-turned terminal, D¹, 35 ending in a V-shape, and the cooperating forks of the cutter-vibrating lever, instead of the up-standing bosses, E, have each a V-shaped slot, E¹. In this form the rear end of the pressure plate is stepped on and spaced upwardly from 40 the cutter vibrating lever, by short pins, C¹, in lieu of the screw, C, of the first form. The tension cup, G, in this form is in the same relation to the front and rear end spacing features, D¹ and C¹, as in the first form; hence,—equally as in 45 the first form,—the tension applied by the tension pin when set in the cup, applies the pressure to the cutter-vibrating lever only at the bearing on the latter of the features, D¹ and C¹, and no bending or flexing of the lever or of either of the 50 forks can occur.

In some makes of sheep shears the lodgement of the rear side of the vibrating cutter is over a center post upstanding from the base of the shell of the shear, and in that type of shear the cutter- 55

vibrating lever is relieved of the pressure from the rear end of the pressure plate.

In the form shown in Figures 7 and 8, the cutter-vibrating lever F^2 is of the form commonly called "chicken foot",—having four prongs or toes for engaging the cutter. In this form the pressure plate B^2 is supported at both ends in the same manner as in the preceding forms, with the V-shaped front D^2 of the pressure plate resting on the prongs. At the engagement of the prongs with the forked lever they may be slightly flattened instead of being recessed for their contact with the V-shaped end B^3 of the pressure plate B^2 , which then merely rests upon them instead of having the edge inserted in the slot.

As a modification of this form there may be provided,—to be mounted, if desired, on the front end, D^2 , of the pressure plate,—one or more movable plates, K , seen in front elevation in Figure 9, and in edge view in Figure 10. These plates are mounted, as stated, by means of a pin, n , rigid with the plates respectively, and constituting pivots for the plates, the pins being inserted in holes in the part, D^2 , and secured by lock pins offset through the pins, n , behind the part, D^2 . The plates, K , extending down slightly below the lower edge of the part, D^2 , of the pressure plate, B^2 , engage the prongs of the cutter-vibrating lever F^2 by means of pin teeth, H , near the point at which they press upon the cutter blade. In this type the plate, B , is made of any suitable length so that the leverage desired may be obtained by virtue of the dimensions.

The plates, K , turning about the axes of the pivot pins respectively, will conform to any unevenness of the prongs resting on the cutter blade, such unevenness sometimes resulting from inaccuracy in grinding the cutters and so preventing the prongs from always seating in a straight line. By this means of adapting this type of pressure plate for cooperation with a cutter-operating lever of the four-prong type, greater resistance of the wool (which must be overcome to obtain even shearing) is overcome with less pressure on the tension pin. Since each fork of the lever has two prongs, and acts by these

prongs on the cutter at two points in its length, it is necessary for the proper functioning of such part as plate, K , that there should be at least two of these plates independently pivoted as described.

I claim:

1. A construction for the purpose indicated comprising in combination a vibrating cutter, a power-operated fulcrumed lever having operative engagement with the cutter for vibrating the latter, a pressure-transmitting plate overlying the lever and having projections from its under side bearing on the lever at points proximate the forward end and the fulcrum of the lever and spacing the plate over the lever intermediate said points of bearing, and means for applying pressure to the pressure-transmitting plate at a point in its length intermediate said projections. 10

2. The construction defined in claim 1, the lever being forked, with prongs spaced apart in the path of vibratory movement of the fork arms, the pressure-transmitting plate having its front end comprising parts extending transversely for overhanging the spaced-apart prongs of the lever fork arms. 25

3. The construction defined in claim 1, the lever being formed at the forward end on the upper side for stopping the pressure-transmitting plate in forwardly endwise movement with relation to the lever. 30

4. The construction defined in claim 1, the pressure-transmitting plate having the forward-end projection V-shaped for engaging the lever, and the lever having in its upper surface at the forward end a V-shaped groove for receiving the 35 V-shaped projection of the pressure plate.

5. The construction defined in claim 1, the cutter-vibrating lever being forked with prongs spaced apart in the path of vibration of the lever, and the pressure-transmitting plate having the 40 projections at the forward end for bearing on the lever formed with the bearing edge continuous and uninterrupted for a length overhanging all the prongs of the lever fork arms. 45
